REUBIN HAMBLIN, OF MISHAWAKA, INDIANA.

Letters Patent No. 65,905, dated June 18, 1867.

IMPROVED CLOTHES-DRYER.

The Schedule referred to in these Letters Patent and making part of the same.

TO ALL WHOM IT MAY CONCERN:

Be it known that I, REUBIN HAMBLIN, of Mishawaka, in the county of St. Joseph, and State of Indiana, have invented a new and improved Clothes-Dryer; and I do hereby declare that the following is a full, clear, and exact description thereof, which will enable others skilled in the art to make and use the same, reference being had to the accompanying drawings, forming part of this specification, in which—

Figure 1 is a top view of my improved clothes-dryer.

Figure 2 is a vertical section of the same, taken through the line $z z$, fig. 1.

Similar letters of reference indicate like parts.

My invention has for its object to furnish an improved apparatus for drying clothes, by means of which a large drying surface may be supplied while occupying a small amount of space; and it consists in the combination of one or more sets or tiers of jointed radial arms, and connecting or supporting wires or cords, with each other and with the central shaft, as hereinafter more fully described.

A is the central shaft, which, in the drawings, is represented as being pivoted to a standard, B, supported upon feet C, but which may be hung up by means of the eye a' , attached to the upper end of said shaft A. D are radial arms, the inner ends of which are jointed or pivoted to the shaft A, so that they may be folded up out of the way when not required for use. The arms D may be arranged in one, two, three, or four tiers, and there may be eight, twelve, sixteen, or any other desired number of arms in a tier. E are supporting or connecting wires, the inner ends of which are pivoted to the central shaft A, at some distance above the point at which the upper series of arms is connected to said shaft. The outer ends of the wires E are hooked over pins or eyes attached to the outer ends of the upper series of arms D, so that they can be readily unhooked when it is desired to fold up the said arms. F are connecting or supporting wires, the upper ends of which are pivoted to the outer ends of the upper series of arms D, and their lower ends are connected to the outer ends of the next lower series of arms. If more drying surface is required, a wire or cord may be passed through the eyes attached to the outer ends of the radial arms, so as to extend all around the apparatus at the ends of each series of radial arms. If desired, the wires E and F may be replaced with firm and strong cords, which will not stretch much, so that they will hold the arms D in a horizontal position. The dryer may be made of any desired size, according to the purpose for which and the place in which it is designed to be used.

I claim as new, and desire to secure by Letters Patent—

The combination of one or more sets or tiers of jointed radial arms D, and the supporting or connecting wires E and F, or their equivalent, with each other, and with the central shaft A, substantially as herein shown and described and for the purpose set forth.

REUBIN HAMBLIN.
